UNITED STATES PATENT OFFICE.

JOSEPH F. MUSSelman, OF BRONXVILLE, NEW YORK, ASSIGNOR TO ANTI-CORROSION ENGINEERING COMPANY, INC., A CORPORATION OF NEW YORK.

VACUUM REGULATOR.

Application filed September 18, 1920. Serial No. 411,259.

To all whom it may concern:

Be it known that I, JOSEPH F. MUSSelman, citizen of the United States, and resident of Bronxville, in the county of Westchester and State of New York, have invented certain new and useful Improvements in Vacuum Regulators, of which the following is a specification.

This invention relates to a vacuum regulating device, adapted for many uses but practically designed for use in connection with apparatus for removing the free gases from water to be used in boilers, economizers, heating systems, etc., to reduce the corrosive effects of the water upon the parts hereof.

The invention has for an object to provide a simple and efficient device of novel construction and arrangement whereby the vacuum in a chamber or conduit through which the water passes may be regulated automatically so as to maintain a substantially fixed differential between that degree of vacuum under which the water would boil and the degree of vacuum actually maintained throughout any temperature change in the water passing, within certain predetermined limits.

A further object of the invention is to also provide means for regulating, in a like manner, the vacuum regardless of the rate of flow of the water through said chamber and the corresponding rate at which the gases are required to be removed therefrom. It will be understood in this connection that the increased rate of flow increases the volume of water and, consequently, the amount of gases removed therefrom, which would normally tend to reduce the vacuum in the chamber, the function of this feature of the invention being to regulate the vacuum under these conditions.

A further object of the invention is to provide a single unitary device in which both of the above regulating means are combined and arranged to co-operate to produce the required regulation of the vacuum under all conditions actually met with in use of such devices.

For further comprehension of the invention, and of the objects and advantages thereof, reference will be had to the follow-

ing description and accompanying drawings, and to the appended claims in which the various novel features of the invention are more particularly set forth.

Fig. 1 of the drawings is a sectional view of a device constructed according to my invention.

Fig. 2 is a diagrammatic elevation showing an application of the invention in connection with a water-jet vacuum pump.

Fig. 3 is a similar view to Fig. 2 but showing an application of the invention in connection with a stream driven vacuum pump.

Fig. 4 is a similar view to Figs. 2 and 3 but showing an application of the invention in connection with an electrically driven vacuum pump.

In the embodiments of the invention as herein shown, the water to be treated is passed through a suitable tank 1 and the regulating device is connected to the water supply pipe leading to said tank and also with the air space in said tank.

The device as here shown (Fig. 1) comprises a vertically elongated chamber or casing 2 having an inlet port 3 on one side near the lower end thereof and an outlet port 4 on the opposite side approximately midway between its upper and lower ends. A pipe 5 (Figs. 2-4) connects to the inlet port 3, and a pipe 6 leads from the outlet port 4 to the tank 1. A discharge pipe 7 leads away from the tank 1. It will be understood, of course, that the pipes 5, 6 and 7 are connected in the desired circulation system. From the casing 2, at a point above the outlet port 4, a small pipe 8 leads to the air space in tank 1, a second small pipe 9 leading from this air space to a suitable vacuum pump, as will be further set forth.

Within this casing 2 are located one or more, (in the present preferred embodiment a series of three) expandible and contractible devices which are connected to the control means for the vacuum pump to which pipe 9 leads. These devices, as here shown, each comprise a circumferentially corrugated tube 10, preferably of thin copper, connected at opposite ends to heads 11 and 12 to form a sealed chamber. These devices may be termed expansion cylinders.

In the present instance, I have shown

three of the cylinders connected together in tandem in vertical axial alinement and numbered, respectively, 13, 14 and 15. Of these cylinders the two lower ones are arranged close together and below the level of the water flowing through the casing 2 from inlet 3 to outlet 4, the normal water level when the device is in operation being indicated by the dotted line X. The upper cylinder 13 is spaced a distance above the two lower ones, being located in the upper part of the casing and at a distance above the normal water level.

These cylinders may be connected together and to the bottom of the casing 2 by suitable means. As here shown, the bottom head 11' on the cylinder 15 has an integral screw 16 on the lower side thereof which is threaded through the bottom of the casing 20 and may have a nut 17 screwed on its projecting lower end. Similarly, the bottom head of the cylinder 14 has an integral screw 18 on its lower side which engages in a socket element 19 on the upper head of the cylinder 15. The top and bottom heads of the cylinders 13 and 14 are also formed with tapped socket elements 20 in which engage opposite ends of a rod 21, which may be guided in a suitable eye formed on the 25 end of a fixed bar 22 projecting inwardly from one side of the casing 2. The top head 11 of the upper cylinder 13 has connected thereto the lower end of a valve-stem rod 23 which extends upwardly through a cover 30 35 forming the top of the casing 2 and is connected at its upper end to a valve 25 of any well known balanced type, in the application of the invention shown in Figs. 2 and 3. Instead of employing a stuffing box 40 to prevent leakage of air past the rod 23, I prefer to employ a similar corrugated tube section, as indicated at 26, which surrounds the rod 23 and is connected at one end to the cover 24 and at its opposite end to the rod 23 45 and expands and contracts as the latter moves. This tube section 26 is formed at its lower end with an outturned flange 26' which rests upon a flat-topped boss 27 on the cover 24 and is clamped tightly thereon by a cap 28 screwed upon said boss. The upper end of this tube section is soldered or otherwise secured to a disk 29 on the rod 23, which disk may be held in place by nuts 30.

In use, the lower cylinders 14 and 15 are wholly or partially filled with a volatile liquid, such as alcohol, ether, etc., while the top cylinder 13 is filled with air or some permanent gas.

In the application of the invention shown in Fig. 2 of the drawing, the valve 25 is placed in a pipe 32 leading from a supply of water under pressure to a water jet vacuum pump 33 of ordinary construction, to which pump the pipe 9, above referred to, 65 also connects.

In the application of the invention shown in Fig. 3 the valve 25 is placed in a steam supply pipe 34 which leads to a steam engine 35 coupled to a vacuum pump 36 to which pipe 9 leads.

In the application of the invention shown in Fig. 4 the valve 25 is dispensed with, and the upper end of the rod 23 is connected to the handle 37 of an electric current supply controller 38 placed in the circuit, indicated 75 generally at 39, to an electric motor 40 which operates a vacuum pump 41.

The device as here constructed is adapted to operate to regulate the vacuum in tank for variations of temperature of the water 80 and for variations in the amount or rate of gas given off by the varying amounts of water flowing to or through the tank, acting to decrease the vacuum when the temperature of the water increases, and vice versa, 85 and maintaining the proper vacuum during variations in the amount of gas to be removed at different rates of flow of water; the manner in which it operates being as 90 follows:—

The expansion cylinders 13, 14 and 15 are so constructed and connected to the valve 25 (or controller 38) as to cause the required vacuum, determined by previous experiment, to be maintained in the tank 1 for 95 water at a given temperature. If the temperature of the water rises the expansion of the volatile liquids in the cylinders 14 and 15 will cause the rod 23 to move upward and operate valve 25 (or controller 38) to slow down the vacuum pump controlled thereby and so decrease the vacuum in the tank 1, a reverse operation taking place when the temperature of the water falls. If the flow of water increases, causing an 100 increase in the volume of gas given off, the vacuum normally will tend to decrease, but decrease of vacuum will cause the upper cylinder 13 to contract, it being apparent that the same air condition is maintained in 110 the casing 2 as obtains in the tank 1, and decrease in the vacuum results in a decrease of the pressure between the inside and outside of the cylinder 13. As the upper cylinder 13 contracts it causes the valve 25 (or controller 38) to operate to speed up the 115 vacuum pump so that the vacuum is restored and maintained. The pipe 9 has a check valve 9' therein to prevent back-flow of the air from the pump to the tank.

It will be noted that when the cylinders 14 and 15 expand under an increase of temperature and decrease the vacuum, the lowered vacuum will cause the upper cylinder to contract in opposition, but it is to be understood that the different cylinders are so proportioned that a neutralization will not take place and the combined net result of the two movements will produce the desired change of vacuum for the change of 130

temperature and thus automatically maintain a predetermined relationship between the same.

It will, of course, be understood that the 5 number of expansion cylinders may be varied, the two lower cylinders being combined in one, etc., or other changes and modifications made in the invention as herein disclosed without departing from the 10 spirit and scope thereof.

What I claim is:

1. In combination with a chamber adapted to have water circulate therethrough, means for creating a vacuum in said chamber, and 15 a plurality of connected and co-operating means for automatically regulating said vacuum creating means according to the volume of gas given off by and temperature of the water flowing through said chamber 20 and adapted to maintain a predetermined differential relationship between the temperature of the water and the degree of vacuum in the chamber.

2. In combination with a chamber adapted 25 to have water circulate therethrough, means for creating a vacuum in said chamber, and means for automatically regulating said vacuum creating means according to the volume of gas given off by and temperature 30 of the water flowing through said chamber, said means including a plurality of expansible elements one of which is immersed in the water and contains a volatile liquid and the other is located in the vacuum 35 space and contains a permanent gas.

3. In combination with a chamber adapted to have water circulate therethrough, means for creating a vacuum in said chamber, and means for automatically regulating said 40 vacuum creating means according to the volume of gas given off by and temperature of the water flowing through said chamber, said means including a plurality of expansible elements one of which is immersed 45 in the water and the other is located in the vacuum space, said elements being connected together in tandem to operate through one another.

4. A device of the class described comprising a casing having intake and outlet ports, adapted to have a fluid circulate therethrough, means for varying the pressure on said fluid in said casing, an expansion cylinder located in the lower end of 50 said casing with its bottom fixed against movement and containing a volatile liquid, a second expansion cylinder located above said first cylinder and having its lower end rigidly connected to the upper end of said 55 first cylinder and containing a permanent gas, and means connecting the upper end of 60

said second cylinder to a part to be operated, whereby a predetermined relationship is automatically maintained between the temperature of the fluid and the pressure in said 65 casing.

5. A device of the class described comprising a casing having intake and outlet ports, adapted to have a fluid circulate therethrough, means for varying the pressure on said fluid in said casing, the intake port being located near the bottom of the casing and the outlet port at a higher level than the intake port, an expansion cylinder located in the lower end of said chamber 70 with its bottom fixed against movements and containing a volatile liquid, a second expansion cylinder located above said first cylinder and outlet port and having its lower end rigidly connected to the upper end of said first cylinder and containing a permanent gas, and means connecting the upper end of said second cylinder to a part to be operated, whereby a predetermined relationship is automatically maintained between the temperature of the fluid and the pressure in said casing.

6. A device of the class described comprising a casing having intake and outlet ports, adapted to have a fluid circulate 90 therethrough, means for varying the pressure on said fluid in said casing, an expansion cylinder located in the lower end of said casing with its bottom fixed against movement and containing a volatile liquid, a second expansion cylinder located above said first cylinder and having its lower end rigidly connected to the upper end of said first cylinder and containing a permanent gas, said expansion cylinders being made up 95 of circumferentially corrugated tubing, and means connecting the said second cylinder to a part to be operated, whereby a predetermined relationship is automatically maintained between the temperature of the fluid 100 and the pressure in said casing.

7. A device of the class described comprising a casing having intake and outlet ports, adapted to have a liquid flow therethrough, the intake port being located near the bottom of the casing and the outlet port at a higher level than the intake port, and an expansion cylinder located in said casing in position to be immersed in the liquid flowing therethrough and operatively connected to and adapted to control a pressure regulating means adapted to regulate the pressure on the liquid in said casing.

Signed at New York city, in the county of New York and State of New York, this 120 14 day of September, A. D. 1920.

JOSEPH F. MUSSELMAN.
